UNITED STATES PATENT OFFICE.

MICHAEL J. DE GRAVE, OF CHICAGO, ILLINOIS.

CURTAIN STRETCHER.

Application filed October 25, 1920. Serial No. 419,379.

To all whom it may concern:

Be it known that I, MICHAEL J. DE GRAVE, a citizen of the United States, and a resident of the city of Chicago, county of Cook, and 5 State of Illinois, have invented certain new and useful Improvements in Curtain Stretchers, of which the following is a specification.

My invention relates to curtain stretchers 10 and it has for its principal object the provision of a new and improved arrangement of parts by which an effective stretching operation can be carried out, which arrangement of parts is simple and not likely to be broken 15 or disarranged in use.

Other objects will appear hereinafter.

The invention consists in the combination and arrangements of parts hereinafter described and claimed.

20 The invention will be best understood by reference to the accompanying drawings forming a part of this specification, and in which,

Fig. 1 is a plan view of my improved 25 stretching apparatus;

Fig. 2 is an enlarged detail view, being substantially a vertical cross section taken on line 2—2 of Fig. 1;

30 Fig. 3 is an enlarged detail view being substantially a section taken on line 3—3 of Fig. 1.

Fig. 4 is a side view of one end portion of one of the rollers employed, showing a modified form of construction.

35 Fig. 5 is a cross section taken on line 5—5 of Fig. 1 but shown in inverted position illustrating the adjustable connection between two of the stretcher bars.

Fig. 6 is a top plan view of the parts 40 shown in Fig. 5; and

Fig. 7 is a perspective view of one of the adjustable curtain engaging pins.

Referring to the drawings, 10 and 11 indicate the side bars of a rigid frame, the 45 end bars of which are indicated by the numerals 12 and 13. The frame bars are arranged in spaced relation with respect to each other and are connected together at their end portions by means of bolts 14 of any approved type. Diagonally disposed brace bars 15 are connected between the end bars and one of the side bars as is shown in Fig. 1 for holding the frame rigidly against distortion.

55 A cross bar 16 is slidably mounted upon the frame, being held in position upon the

frame by means of clips 17 which are mounted upon the cross bar and extend about the end bars 12 and 13 in the manner illustrated in Fig. 5, in such relation that 60 the cross bar 16 is slidable laterally with respect to the rigid frame. A second cross bar 18 is slidably mounted upon the frame at right angles to the cross bar 16, being provided with a clip 19 mounted thereon and extending about the side bar 10 so as to permit a sliding movement of the bar 18 longitudinally of the frame. Each of the bars 10, 12, 16 and 18 is provided with a dove-tailed groove 20 as is best shown in connection with the bar 12, in Fig. 5, the grooves 20 being such as to hold slidably in position therein a series of pin members 21, as is best shown in Fig. 2. As will be readily understood, the pin members 21 are 75 adapted to be slid along the bars to any desired position for holding the edge of one or more curtains which are to be stretched in the well known manner. Means is provided for regulating the position of the 80 cross bars 16 and 18 with respect to the bars 10 and 12 for accommodating curtains of different sizes, as is usual in devices of this type.

The means for controlling the position of the slidably mounted bar 16 comprising flexible tapes 22 which are connected at their ends to the bar 16 and which are connected at their other end portions to a roller 23 which is revolubly mounted between brackets 24 carried by the frame bar 11, the arrangement being such that the tapes are adapted to be wound about the roller as is best shown in Fig. 2. Spring devices 25 are mounted upon the side bar 11 in position to bear yieldingly against the roll of tape at the ends of the roller 23, as is best shown in Fig. 2, the pressure of the spring devices 25 being such as to resist the unwinding of the tapes 22 from the roller for 100 preventing racing of the roller. The cross bar 18 likewise has connected to it two tapes 26 which are adapted to be rolled about a roller 27 revolubly mounted upon the end bar 13, spring devices 28 being provided 105 for resisting the unwinding of the tapes as above described.

In addition to the friction-controlled means for regulating the unwinding of the tapes 22 and 26, positively acting means is 110 also provided for limiting the unwinding operation. This means for each of the sets

of tapes comprises a ratchet wheel 29 mounted upon the tape roller at one end and a double acting pawl 30 adjustably mounted adjacent to the ratchet wheel in position to co-operate therewith. In the construction shown, the pawl 30 is pivotally mounted between the bracket 24 and a smaller bracket 31 mounted adjacent thereto, as is best shown in Fig. 3. As is shown 10 in said Fig. 3, the pawl 30 comprises a handle portion 32 and two teeth 33 and 34 on opposite sides of the axis about which the pawl is pivotally mounted. A spring 35 is provided bearing against suitable portions of the pawl 30 for holding it in either one of two alternative positions as shown in Fig. 2, with the tooth 33 in engagement with the ratchet wheel as is shown in solid lines in Fig. 2 or with the tooth 34 in engagement with the ratchet wheel as is shown 20 in dotted lines. As will be readily understood, when the pawl is in the position shown in solid lines in Fig. 2, the roller 23 is held against rotary movement in the direction for unwinding the tapes 22. On the other hand, when the pawl is in the position shown in dotted lines in said Fig. 2, the roller is held against rotary motion in the direction for winding the tapes thereon. 25 As will be readily understood, by connecting the tapes for each of the bars 16 and 18 with a single roller as is shown in Fig. 1, so that a rotary movement of the roller for unwinding the tapes serves to give out an equal length of tape at each end of the roller, the slidably mounted bar is prevented from assuming a diagonal position with respect to the frame bars, the tapes and their co-operating parts acting as an 30 equalizer or evener for maintaining the slidably mounted bars in shifting parallel positions. By the provision of the spring devices 25 and 28, in connection with the other tape controlling means, I am enabled 35 to regulate the positions of the slidably mounted bars to very good advantage. By the use of the pawl and ratchet mechanism, the bars 16 and 18 are adapted to be held positively against movement away from the 40 bars 11 and 13 respectively, and automatically held in parallel position with respect to such bars. 45 In Fig. 4, which shows a modification, the same reference characters are employed, in 50 as much as the change consists merely in the mounting of the pawl and ratchet mechanism at the opposite end of one of the rollers as compared with the showing of the remaining figures of the drawing. As 55 will be readily understood, the operation of the device as shown in Fig. 4 is precisely the same as that already described.

As is best shown in Fig. 7, the pin member 21 comprises an engaging point 36, a handle portion 37 and a rectangular base portion 38 by which the member is held in position, the form of the base 38 being such as to prevent the member from becoming stuck in the groove 20. 65

While I have illustrated and described the preferred form of construction for carrying my invention into effect, this is capable of variation and modification without departing from the spirit of the invention. I, therefore, do not wish to be limited to the 70 precise details of the construction set forth, but desire to avail myself of such variations and modifications as come within the scope of the appended claims. 75

Having described my invention, what I 80 claim as new and desire to secure by Letters Patent, is:—

1. In a curtain stretcher, the combination of a rigid frame having longitudinally extending grooves for the reception of a series of curtain pins; cross bars slidably mounted on said frame substantially at right angles with respect to each other; brackets mounted adjacent the ends of one of the side and end bars of said frame; rollers revolvably mounted on said brackets; flexible tapes connected to said cross bars and adapted to be wound on said rollers; a ratchet wheel mounted on the end of each of said rollers; and a spring held double acting pawl adapted upon engagement with said ratchet wheel to alternately lock said roller against winding and unwinding operation, substantially as described. 90

2. In a curtain stretcher, the combination of a rigid frame having longitudinally extending grooves for the reception of a series of curtain pins; cross bars slidably mounted on said frame substantially at right angles with respect to each other; brackets mounted adjacent the ends of one of the side and end bars of said frame; rollers revolvably mounted on said brackets; flexible tapes connected to said cross bars and adapted to be wound on said rollers; a ratchet wheel mounted on the end of each of said rollers; a double acting pawl engaging said ratchet wheel; resilient means for holding said pawl in engagement with said ratchet wheel; and an operating handle formed on said pawl, substantially as described. 100

In testimony whereof I have signed my name to this specification in the presence of two subscribing witnesses.

MICHAEL J. DE GRAVE.
